ATTYS

UNITED STATES PATENT OFFICE.

WILLIAM P. STRICKLAND, OF CHICAGO, ILLINOIS.

NIPPLE-GRIP.

1,393,920.

Specification of Letters Patent.

Patented Oct. 18, 1921.

Application filed November 20, 1920. Serial No. 425,512.

To all whom it may concern:

Be it known that I, WILLIAM P. STRICKLAND, a citizen of the United States, and a resident of Chicago, in the county of Cook 5 and State of Illinois, have invented a new and useful Improvement in Nipple-Grips, of which the following is a full, clear, and exact description.

My invention relates to improvements in 10 nipple grips, and it consists in the combinations, constructions, and arrangements herein described and claimed.

An object of my invention is to provide 15 a device for engaging a spoke of a bicycle or the like and the spoke nut thereon to permit operation of the latter without subjecting the device to a lateral stress.

A further object of my invention is to 20 provide a device of the type described that can be adjusted quickly and easily to operatively engage work of varying sizes.

A further object of my invention is to 25 provide a device of the type described that comprises comparatively few parts and is therefore durable and can be used indefinitely in service.

A further object of my invention is to 30 provide a device of the type described that is simple in construction and operation, can be manufactured cheaply, and is thoroughly practical commercially.

Other objects and advantages will appear 35 in the following specification, and the novel features of the invention will be particularly pointed out in the appended claims.

My invention is illustrated in the accompanying drawings, forming part of this application, in which

Figure 1 is a view of the device opera- 40 tively applied,

Fig. 2 is a side elevation of the device,

Fig. 3 is a section along the line 3—3 of Fig. 1.

I am aware that many tools of the same 45 character as my device have been provided prior to my invention. Such devices are composed of a comparatively great number of parts and are therefore liable to be broken under ordinary service conditions. Further- 50 more, such devices are subjected to a lateral stress when a spoke nut or nipple thereon is operatively engaged. My device consists of a body portion having integral arms forming jaw members and therefore cannot 55 be broken easily. In addition, my device

has means for gripping a spoke nut without being strained laterally.

In carrying out my invention, I provide a body portion comprising a web 1, having integral arms 2 and 3 formed to provide 60 jaws 4 and 5 respectively at the ends thereof. The arms 2 and 3 are normally substantially parallel. The body portion is made of a material such as spring steel having sufficient inherent resiliency to permit 65 the arms 2 and 3 being moved under stress toward each other and to insure that the arms 2 and 3 will swing back to the initial position when the stress is removed.

Obviously, the arms 2 and 3 can be moved 70 by any force sufficient for that purpose to cause the jaws 4 and 5 to engage opposite sides of a spoke nut or nipple 6 or the like that is thereupon gripped between the jaws. In order to maintain the jaws 4 and 5 in 75 operative position with respect to the spoke nut 6, I provide an adjusting bolt 7 that is projected through registering openings 8 and 9 extending transversely through "em- 80 bosSED" portions 10 and 11 of the arms 2 and 3, respectively, adjacent the ends thereof. The bolt 7 has a non-circular head 12 ar- 85 ranged to enter a slot 13' in the side edge of the arm 3, wherefore rotation of the bolt 7 is prevented. A jam nut 13 screwing on 85 the threaded end 14 of the bolt 7 provides a convenient means for occasioning a move- 90 ment of the arms 2 and 3 relative each other and for maintaining the same in adjusted position.

From the foregoing description of the various parts of the device, the operation thereof may be readily understood. The device is placed in the position shown in Fig. 1 relative a spoke 15 of a bicycle wheel or 95 the like. The spoke 15 is threaded at 16 and has the usual spoke nut 6 screwing thereon, the outer end of the spoke nut 6 being flanged at 17 for engagement with a rim 18 of a bicycle wheel, this being the conventional construction. The spoke 15 is "tightened" or "loosened" by turning the spoke nut 6. When the device is applied thereto in the manner shown, the nut 13 is operated until the spoke nut 6 is firmly 100 gripped by the jaws 4 and 5. At this time, the web 1 will be maintained in a desired position relative the spoke 15 by means of an integral hook 19 that is positioned to intersect the plane equi-distant between the 110

adjacent faces of the jaws 4 and 5 and therefore in position to receive the spoke 15. The bolt 7 is provided with a groove 21 spaced from the head thereof so that its grooved portion is disposed between the registering openings 8 and 9. The portion of the spoke 15 contacting with the bolt 7 is received within the groove 21, which is of sufficient depth to prevent lateral stress being placed 10 on the device 15 when the same is operatively applied, as illustrated in Fig. 1. Consequently, the operation of the device occasions no strain of the spoke 15 or its connections with the rim and hub of the wheel, or 15 of the device itself.

The device is simple in construction, effective for the purpose intended, and can be used in service for an indefinite length of time. Since the jaw members are embodied 20 in the same body portion, the device is not likely to be broken.

It will be noted that the jaws 4 and 5 have their ends beveled at 20—20 and that the beveled portions thereof taper rearwardly as 25 shown. The device can therefore be turned to adjust the spoke nut without being moved into engagement with the circular inner wall of the rim or felly 18.

I claim:

30 1. A device of the character described comprising a body portion having substantially parallel arms formed to provide jaws at the forward ends thereof and having a hook at the rearward end thereof positioned 35 to receive a portion of the work disposed between said jaws, and means for adjusting said jaws relative each other to grip work of varying sizes placed therebetween and for maintaining said jaws in adjusted position.

40 2. A device of the character described comprising a body portion of resilient material having substantially parallel arms formed to provide jaws at the forward ends 45 thereof and having a hook at the rearward end thereof positioned to receive a portion of the work disposed between said jaws, and means for adjusting said jaws relative each

other to grip work of varying sizes placed therebetween and for maintaining said jaws 50 in adjusted position.

3. A device of the character described comprising a body portion having substantially parallel arms formed to provide jaws at the forward ends thereof and having a hook at the rearward end thereof positioned to receive a portion of the work disposed between said jaws, said jaws having beveled ends tapering rearwardly, and means for adjusting said jaws relative each other to 60 grip work of varying sizes placed therebetween and for maintaining said jaws in adjusted position.

4. A device of the character described comprising a body portion having substantially parallel arms formed to provide jaws at the forward ends thereof and having a hook at the rearward end thereof positioned to receive a portion of the work disposed 65 between said jaws, a non-rotatable bolt projected through registering transverse openings through said arms adjacent said jaws, and a jam nut screwing on the end of said bolt for adjusting said jaws relative each other to grip work positioned therebetween. 70

5. A device of the character described comprising a body portion having substantially parallel arms formed to provide jaws at the forward ends thereof and having a hook at the rearward end thereof positioned 75 to receive a portion of the work disposed between said jaws, said arms being formed with registering transverse openings therethrough adjacent said jaws, a non-rotatable bolt projected through the registering transverse openings through said arms, said bolt having the portion thereof extending between the adjacent sides of said arms grooved to receive a portion of the work positioned 80 between the jaws, and a jam nut screwing on the end of said bolt for adjusting the jaws to grip the work to permit operation thereof without subjecting the body portion to a lateral stress. 85

WILLIAM P. STRICKLAND.
